FLUORESCENT LAMP SHADE

Nathan R. Schwartz, Yonkers, N.Y., assignor to Naras
Research Inc., New York, N.Y., a corporation of New
York

Filed Dec. 22, 1958, Ser. No. 53,865

Term of patent 14 years

(Cl. D48—20)

FIG. 1

FIG. 2

FIG. 3

FIG. 4

FIG. 5

FIG. 6

FIG. 8.FIG. 9.FIG. 7.FIG. 10FIGURE 1 is a rear elevation of a fluorescent lamp shade showing my new design.

FIGURE 2 is a top plan view thereof.

FIGURE 3 is a bottom plan view thereof with certain details of the lens being only partially shown and it being understood that said details cover the entire lens shown except for the central portion.

FIGURE 4 is a front elevation thereof.

FIGURE 5 is a side elevation thereof.

FIGURE 6 is a cross-sectional view of FIGURE 4, taken along the lines 6—6 and looking in the direction of the arrows.

FIGURE 7 is a cross-sectional view of the surface shown in FIGURE 4 taken along the lines 7—7 and looking in the direction of the arrows.

FIGURE 8 is a perspective of a fragment of the lens illustrated in the plan view of FIGURE 3.

FIGURE 9 is a cross-sectional view taken along the lines 9—9 of FIGURE 3 and looking in the direction of the arrows.

FIGURE 10 is a fragmentary perspective view thereof as seen from the bottom and opposite side of FIGURE 5.

I claim:

The ornamental design for a fluorescent lamp shade, as shown and described.
